Horace of Shumway of Van Buren N. York
Setters Patent

The Schedule referred to in this Letter Patent and making part
of the same containing a description in the words of the said
Horace of Shumway himself of his improvement in making
Water Cisterns, Cider Vaults, Salt Vats or reservoirs, fish ponds etc.

To all whom these presents shall come. Be it known that I
Horace of Shumway of the town of Van Buren in the County of One
ida, and State of New York, have invented a new and useful
improvement in making Water Cisterns, Cider Vaults or Cisterns,
Salt Vats or Reservoirs, Fish Ponds, Jamers Vats, and such other
cisterns vats vaults, Reservoirs &c as may be necessary for holding large
quantities of liquids, and that the following is a full and exact de
scription of the operation of building and constructing said cisterns
vats, vaults Reservoirs ponds &c above mentioned, as invented or im
proved by me viz. First, for constructing cisterns vats, vaults or
Reservoirs or ponds which may be required to be built below the
surface of the earth, dig or excavate the earth forming a hole
of the required shape and dimensions. Then if by reason of springs
stone or other causes, a smooth and even surface of wall and bottom
is not obtained, other earths as sand, clay, loam, or gravel,
or a mixture of these is to be used to fill the cavities and thus
form a smooth and even surface of bottom and wall,
this done the bottom and wall is to be spread or plastered
over with this mortar formed as aforesaid, viz Water Lime
and water mixed together in the proportion now used or such
other proportions as the nature of the earth, in which the cistern,
vat vault, Reservoir or Pond is to be built or constructed may
be required to form a cement. If by reason of springs or
other causes, a greater consistency of mortar is required than
can be easily obtained by the mixture of the water lime, sand

and water, gravel may be used, and either mixed in with, or making the mortar, or sprinkled on to the same after having been placed or spread on and partially or wholly imbedded while the mortar is yet green or soft. This done, and the first coat having obtained a sufficient hardness or consistency to receive a second, it should be immediately applied and the graveling repeated, and so on until the wall shall have attained the required thickness. Cisterns Vats, Vaults or Reservoirs, thus formed either with or without the gravel, and which require to be covered with either wood or stone are to be done by first preparing a foundation for the covering, to rest upon on the outside of the wall of cement so that the covering may not rest upon the wall of cement, then put on the covering, which is to be so neatly fitted to the top of the wall that by plastering upon the underside of the covering there may be a continuation of the walls all over the whole exterior of the Cistern Vat, vault, or reservoir.

Of the above covering is made of wood a coat of mortar ought to be spread over the whole outside to prevent decay. In the cover there may be left a hole, or a tube inserted through which the liquid is to pass into the Cistern vault, vat, &c as above, and also another hole of any convenient size out of which to draw the liquid and if large this ought and is to be protected by a curb and this curb covered with a lid. A drain may also be necessary, and for this purpose a small aperture or opening should be left or a tube inserted in such a manner as to prevent any waste of the cement. It is construed or build any of the above named articles, which shall or may be required to be built upon or above the surface of the earth, a frame or mould will be necessary, and when made of wood the outside should be protected from frost and decay by a coat of Plaster, or otherwise, and the inside may be plastered without (and with the use of gravel) with a mortar made as aforesaid. The particular

advantage when this method of constructing, or building cisterns, wells, tanks, reservoirs and ponds which are to be sunk below the surface of the earth, by plastering upon the bare walls of earth instead of first lining the hole or excavation with stone, brick or wood, as is now practised in constructing water cisterns, are numerous, but the principle of which are cheapness and durability. Wood thus exposed will soon decay and leave the wall unprotective. Brick by contraction and expansion crack the walls, and at the same time like stone are expensive. The principal grounds and items for and upon which your Petitioners prays and requests, letter patent are the following viz. 1° For plastering upon the earth-
y walls instead of plastering upon stone, brick, and wood, in
hurtofex and now practised in building, and constructing of cisterns for
holding rain water which may pass through a reafing, before pas-
sing into the cistern by which the water is fit for all uses. 2° You
applying the use of said cement to the constructing and building
of cisterns or vaults, Tunnels, Oats, Mill rats or reservoirs,
fish ponds and other tanks and reservoirs for holding large
quantities of liquids, for which the said cement has not been used
or known. 3° For the use of gravel to stiffen or harden the mortar
which has not been heretofore used in the manner specified
above, or in any other, to form a cement, or stiffen the mortar.

In witness whereof I have hereunto subscribed, my
name & day of November 14th 1833.
